UNITED STATES PATENT OFFICE.

JAMES R. TIMMINS AND ORLANDO SWAIN, OF OKMULGEE, OKLAHOMA.

APPARATUS FOR REFINING OIL.

1,179,243.

Specification of Letters Patent.

Patented Apr. 11, 1916.

Application filed March 8, 1915. Serial No. 12,885.

To all whom it may concern:

Be it known that we, JAMES R. TIMMINS and ORLANDO SWAIN, citizens of the United States, residing at Okmulgee, in the county 5 of Okmulgee and State of Oklahoma, have invented certain new and useful Improvements in Apparatus for Refining Oil; and we do declare the following to be a full, clear, and exact description of the invention, 10 such as will enable others skilled in the art to which it appertains to make and use the same.

This invention relates to the oil-refining industry, and more particularly to apparatus 15 for refining crude oil or its by-products. Heretofore considerable loss has been experienced by those engaged in refining mineral oil due to the intermingling of the lighter with the heavier oils during distillation and 20 it is one of the objects of this invention to provide a distilling apparatus which will enable the products of volatilization from the original stock to be repeatedly evaporated and condensed, whereby the production 25 of the lighter oils may be greatly augmented.

Another and still further object of this invention is the provision of a novel manifold connection wherein the vapors arising 30 from the retort will not be discolored by the descending products of condensation.

Another and still further object of this invention is to provide a plurality of relatively arranged and intercommunicating 35 manifolds wherein an exceptional large condensing area is provided for the volatilized products.

With these and other objects in view, our 40 invention consists of certain novel details of construction, and combination and arrangement of parts as will be more particularly hereinafter set forth and claimed.

In the accompanying drawings in which 45 corresponding parts are indicated by similar reference numerals; Figure 1 is a diagrammatic view; Fig. 2 is a side elevation of a portion of the apparatus showing more particularly the construction and arrangement 50 of the manifolds; Fig. 3 is a transverse vertical section of the cooling tank and tail house; Fig. 4 is a horizontal section taken on the line 4--4 of Fig. 3.

In its illustrated embodiment, our invention 55 comprises a retort or still 1 provided with suitable inlet openings and adapted to retain the crude oil to be refined. Rising

from the central portion of the retort 1 is a dome 2 into which the vapors produced by heating of the retort's contents collect. Extending vertically from the central portion 60 of the dome 2 is a pipe 3 the upper end of which communicates with a cross head 4 into which the vapors of dome 2 ascend. Rising in suitably spaced relation from the cross head 4 are a plurality of conduits 5 65 the free ends of which communicate with the pipes 6 of the vertically disposed manifold 7 having at its lower extremity a cross head 8 to receive the condensate from the pipes 6 which condensate is conveyed from 70 the cross head in a manner hereinafter to be described. For the sake of convenience the manifold or condenser 7 will be termed the primary manifold or condenser. Communicating with the upper ends of pipes 6 of 75 the manifold 7 are a series of pipes 9 which latter comprise what may be termed the secondary manifold or condenser 10. The pipes of the secondary manifold 10 are inclined upwardly from the upper ends of 80 the primary manifold 7. A plurality of vertically disposed pipes 11 which form the tertiary manifold or condenser 12 have their upper ends communicating with the free 85 ends of manifold 10, the lower extremities of the pipes 11 being connected to a cross head 13, one extremity of which is closed, the other opening into a suitably supported receiver 14. To enable the condensate which 90 collects in receiver 14 to be conveyed to the retort 1, the latter is in communication with the receiver 14 by means of a pipe 15 provided with a suitable valve 15' in the length 95 thereof. To conduct the uncondensed vapors from receiver 14 the latter has its upper end communicating with one end of a branch pipe 15'' the other extremity of 100 which communicates with a pipe 16. Moreover to enable the condensate collecting in cross head 8 to be conveyed to the receiver 14, said cross head 8 is in communication with the latter by means of pipe 16'. The pipe 16 extends in one direction to the pipe 3 arising from the retort and in the opposite direction to cross head 17 with which it is 105 in communication by means of a connection 18. As it is desirable that the passage of the vapors through the pipe 16 may be controlled, said pipe has a valve 19 in the length thereof as will be readily understood 110 without further description.

Situated within a cooling tank 20 adapted

to contain any suitable cooling medium, are a plurality of vertically disposed coils 21. The upper ends of the coils 21 are connected with the cross head 17, while the lower ends thereof extend through the rear end of the tank 20 and enter the tail house 22. Within the tail house 22 there is disposed what might be termed, a primary receiver, in the form of a pipe 23, Fig. 3. 5 The free ends of the coils 21 are connected to the pipe 23 as clearly shown in Figs. 3 and 4. Extending from the central portion of the pipe 23 is an oil conducting pipe 24, the free end of which communicates with 10 what might be termed a secondary receiver or pipe 25 also situated within the tail house 22. To enable the operator to be cognizant of the grade of the oil passing through the pipe 24 and at the same time, make suitable 15 hydrometer tests, the pipe 24 has in the length thereof, a T-shaped sight tube 25' by means of which oil may be withdrawn for the purpose of making hydrometer tests and also examined while passing through the tube 20 to determine its quality. As this is the usual 25 construction of any refining apparatus, further description of the same is thought to be unnecessary. Extending from the secondary receiving pipe 25 are three pipes 30 26, Fig. 1, the free ends of which communicate with receivers 27, 28 and 29 respectively. Each of the pipes just referred to is provided with a controlling valve 30 so that the condensate may be caused to pass 35 to any desired receiver.

From the foregoing description it will become apparent that the *modus operandi* of our improved refining apparatus will be as follows: When the crude oil within the 40 retort 1 is heated, the vapors rising therefrom and collecting in the dome 2 will pass upwardly through the pipe 3 into the cross head 4 whence they will pass through the various pipes comprising primary manifold 45 7 to manifold 9. On passing through the primary manifold 7 the heavier vapors of course will be condensed, the condensate collecting in cross head 8 whence it will be conveyed by the pipe 16' to receiver 14. As 50 the lighter vapors pass onward through the pipes of the secondary manifold 10 more of the heavier vapors will be condensed, the condensate descending pipes 9, by reason of the incline of the latter, will enter the pipes 55 of manifold 7 and pass down the same to cross head 8. The residual vapors upon leaving the secondary manifold 10 will pass into the pipe of the tertiary manifold 12 and here again the process of condensation 60 will be repeated, the heavier oils dropping into the cross head 13 whence they will pass to the receiver 14. The heavier oils accumulating in receiver 14 may be returned to the retort by pipe 15, or otherwise used as desired. However, the uncon-

densed or residual vapor collecting in the top of receiver 14 will pass through the pipe 15' to the pipe 16; upon entering the latter it will continue therethrough and through the curved connection 18 to cross head 17. From the cross head 17, these vapors will pass through the various coils 21 within the cooling tank 20 and thence to the receiving pipe 23 in the tail house 22. From receiving pipe 23 the condensate passes 65 through the oil conducting pipe 24 and sight tube 25' to the secondary receiving pipe 25. The different grades of oil may be collected in the various receptacles 27, 28 and 29 respectively. Of course, it is 70 understood in this connection that the receptacle into which the oil is permitted to pass, is determined by the operator who from time to time makes hydrometer tests and according to the disclosure of these 75 tests, opens the valve which gives access to the desired receptacle. However, this structure is of the character usually employed in the industry under consideration and further description with respect to the same 80 is thought to be unnecessary.

It may sometimes be desirable to permit the vapors rising from the retort 1 to pass directly to the coils 21 and when such is the case, valve 8' disposed in the length of pipe 3 is closed and valve 19 in the length of the pipe 16 is opened, consequently the vapors instead of passing through pipe 3 and to the various manifolds as usual, is permitted to pass from the retort to the 100 coils 21. This condensate may be collected and used for any purpose desired.

It will now become apparent that by reason of the increased condensing area provided by the relatively arranged inter-communicating manifolds, together with the connections through the instrumentality of which the products of volatilization may be returned to the primary manifold, and the condensate returned to the retort for further volatilization and condensation, an extremely thorough refining of the heavier oils is obtained, so that the production of light oil from a given amount of mineral oil far exceeds that now obtained by the refining 110 apparatus heretofore in use.

It is also here to be noted with respect to the manifold 7 that owing to the manner in which the latter is connected with the cross head 4 the condensate descending from 115 the pipes 6 of manifold 7 will not collect in the cross head through which the vapors have to pass but will collect in the separate cross head 8 so that consequently all possibility of the condensate discoloring the 120 lighter vapors is eliminated.

Although in the foregoing description we have described certain elements best adapted to perform the functions set forth, it is obvious that various changes in form, propor- 125 130

tion and in the minor details of construction may be resorted to, within the scope of the appended claims without departing from the spirit or sacrificing any of the 5 principles of the invention.

We claim as our invention:

1. The combination of the vapor outlet of a boiler, for conveying the hot gases and vapors to be condensed, a header connected thereto, a primary condenser comprising a plurality of upwardly extending condensing pipes, each connected at its lower end with a condensate collector, an inlet from said header to each of said condensing pipes at a point a short distance above the lower ends of said pipes, whereby the hot gases and vapors are brought for a short time only into contact with the condensate in said condensing pipes, and are then removed from contact therewith, before said condensate can be injured by prolonged contact with said hot vapors and gases, inclined condensing pipes connected at one end with the upper end of each of said upwardly extending pipes, downwardly extending condensing pipes connected with the other end of each of said inclined pipes, means for passing the uncondensed vapors from said primary condenser through a secondary condenser, and a valved by-pass for passing the vapors from said vapor outlet directly into said secondary condenser when desired.
2. The combination of the vapor outlet of a boiler for conveying the hot gases and vapors to be condensed, a header connected thereto, a primary condenser comprising a plurality of upwardly extending condensing pipes each connected at its lower end with a condensate collector, an inlet from said header to each of said condensing pipes at a point a short distance above the lower end thereof, whereby the hot gases and vapors are brought for a short time only into contact with the condensate in said vertical pipes, and are then removed from contact therewith before said condensate can be injured by prolonged contact with said hot gases and vapors, a plurality of inclined condensing pipes, the lower end of each of which is connected to the upper end of one of said upwardly extending condensing pipes, whereby the condensate produced in said inclined pipes can flow back into said vertical pipes, a plurality of downwardly extending condensing pipes each of which is connected to the upper end of one of said inclined pipes, a liquid collecting means at the lower end of each of said downwardly extending condensing pipes, a separating vessel connected with said collecting means, for separating the condensate from the uncondensed gases and vapors, a secondary condenser and means for passing the uncondensed gases and vapors from said separator through said secondary condenser, and a
3. A primary condenser comprising a plurality of vertical pipes, liquid collecting means connected to the lower end of all of said pipes, a vapor inlet to each of said pipes located a short distance above said liquid collecting means whereby the condensate in said vertical pipes will be brought for a short interval only, in the form of a flowing film into contact with the hot gases and vapors entering said condenser, and whereby said condensate will be removed from contact with said hot gases and vapors before said condensate can be injured by prolonged contact with said hot gases and vapors, another series of vertical pipes provided with a liquid collecting means connecting the lower ends thereof, a connection between the upper ends of said first mentioned vertical pipes and the upper ends of said second mentioned vertical pipes, a receptacle connected to each of said condensate collectors, a secondary condenser for condensing the gases and vapors leaving said separating receptacle, and means for bypassing all of said hot gases and vapors around said primary condenser.
4. In a condenser, the combination of a vapor pipe for conveying the hot gases and vapors to be condensed, an upwardly extending condensing pipe, an inlet pipe connecting said condensing pipe at a distance above its lower end and remote from its upper end with said vapor pipe, whereby the hot gases and vapors are brought for a short time only into contact with a film of condensate in said vertical pipe, and are then removed therefrom before said condensate can be injured by prolonged contact with said hot gases and vapors, an inclined condensing pipe of which the lower end is connected to the upper end of said upwardly extending pipe, whereby the condensate in said inclined pipe can run back into said vertical pipe, a downwardly extending condensing pipe connected to the upper end of said inclined pipe, and a liquid collecting means at the lower end of said downwardly extending pipe, connected with a separator, to separate the condensed liquid from the uncondensed gases.
5. In a condenser the combination of the vapor outlet of a boiler, for conveying the hot gases and vapors from said boiler to a condensing system, a primary condenser comprising an upwardly extending condensing pipe, an inlet pipe connecting said condensing pipe, at a distance above its lower end, and remote from its upper end, with said vapor outlet, whereby the hot gases

and vapors entering the said upwardly extending condensing pipe are brought into contact with a flowing film of condensate therein, and whereby said hot gases and vapors are removed from direct contact therewith before said condensate could become injured by prolonged contact with said hot gases and vapors, an inclined condensing pipe of which one end is connected to the upper end of said upwardly extending pipe, a downwardly extending condensing pipe connected to the other end of said inclined pipe, liquid connecting means at the lower end of said downwardly extending condensing pipe, and a separating receptacle connected with said liquid collecting means, capable of allowing the separation of the gases and vapors from the liquid, a secondary condenser connected to said separating receptacle at a point above the normal liquid level therein, for further cooling the gases and vapors leaving said liquid collecting means.

6. A distilling apparatus comprising a boiler, a vapor outlet pipe for conducting the hot gases and vapors from said boiler to a condensing system, a primary condensing system comprising a header connected to said vapor outlet, a series of vertically arranged condensing pipes, all connected at their lower ends to a liquid collecting means, a gas and vapor inlet to each of said vertical pipes from said header, entering said vertical pipes at a short distance above the lower

end thereof, whereby a film of condensate in each of said pipes is brought into contact with the hot gases and vapors entering the primary condenser, for a period of time insufficient to materially injure said condensate, a plurality of inclined condensing pipes, the lower end of each of which is connected to the upper end of one of said vertical pipes, whereby the condensate in said inclined pipes can run into said vertical pipes, a plurality of downwardly extending condensing pipes, each of which is connected at its upper end, to the upper end of one of said inclined pipes, a header connecting the lower ends of said downwardly extending condensing pipes, and connected with a separating receptacle, a connection from said liquid collecting means to said separating receptacle, a vapor outlet from said receptacle to a secondary condensing system, and a by-pass from said vapor outlet pipe directly to said secondary condensing system, whereby said primary condensing system may be disconnected when desired, and a valved pipe for connecting said separating receptacle and said boiler when desired.

In testimony whereof we have hereunto set our hands in presence of two subscribing witnesses.
